UNITED STATES PATENT OFFICE

2,574,857

YIELDABLY MOUNTED TILTABLE SUPPORT
FOR MINE TIMBERING MACHINESCharles F. Ball, Franklin, Pa., assignor to Joy
Manufacturing Company, Pittsburgh, Pa., a
corporation of Pennsylvania

Application May 1, 1948, Serial No. 24,534

12 Claims. (Cl. 214—95)

1

This invention relates to yieldably mounted, tiltable supports and more particularly to a tiltable, spring-mounted, timber support for a timber setting machine.

In a timber setting machine of the type disclosed in a copending application to Felderman and Knoizen, Serial No. 746,832, filed May 8, 1947, there is a timber carrying body mounted on wheels adapted to travel over the floor of a mine. A horizontal arm is pivotally mounted on the body to swing horizontally with respect thereto, and carried at its free end at one end of the body is a telescopic hydraulic jack; and a timber support is elevated by the jack to bring a timber thereon up against a mine roof, and the jack serves to hold the timber up against the roof during setting of the upright props. Since the roof of an underground mine is usually uneven, it is desirable yieldingly to mount the timber support on the jack in such manner as to enable the timber to accommodate itself to the uneven roof, thereby to protect the jack from substantial lateral stresses. In accordance with the present invention, the timber support is spring-mounted on the jack and is transversely tilttable to accomplish the desired results above outlined. The springs are preloaded so that a slight off-balancing of the timber on the support will not cause undesired tilting of the support during elevation of the jack, and the support may tilt against the action of the preloaded springs only when the timber is pressed against the uneven roof and is firmly held there.

It is an object of the present invention to provide an improved yieldably mounted, tiltable support. Another object is to provide an improved transversely tilttable, spring-mounted, timber support for a timber setting machine whereby a timber may be held up against an uneven mine roof. A further object is to provide an improved tilttable, spring-mounted timber support which has a timber receiving platform mounted on preloaded springs so that the support may tilt only when the timber is held with substantial force up against an uneven mine roof. Yet another object is to provide an improved transversely tilttable, spring-mounted support of novel construction whereby extreme vertical compactness is attained. These and other objects and advantages of the invention will, however, here-

2

inafter more fully appear in the course of the ensuing description and as more particularly pointed out in the appended claims.

In the accompanying drawing there is shown for purposes of illustration one form which the invention may assume in practice.

In this drawing:

Fig. 1 is a side elevational view of a timber setting machine with which an illustrative form of the improved tilttable timber support is associated, showing the machine in operating position in a mine, with a timber held up against the mine roof.

Fig. 2 is an enlarged top plan view of the timber support.

Fig. 3 is an enlarged cross-sectional view taken on line 3—3 of Fig. 2, with the spring housings partially broken away to show the spring structure.

Fig. 4 is a side elevational view of the timber support shown in Fig. 2.

Fig. 5 is an enlarged vertical detail sectional view taken on line 5—5 of Fig. 2.

Fig. 6 is an enlarged view in central longitudinal vertical section taken on line 6—6 of Fig. 2, with a tilted position of the platform indicated in dotted lines.

Fig. 7 is a detail vertical sectional view taken on line 7—7 of Fig. 3.

In this illustrative construction, as shown in the drawing, the improved timber support, generally designated 1, is associated with a timber setting machine generally designated 2. Evidently, the improved tilttable support may be associated with other types of apparatus.

The timber setting machine 2, as above mentioned, may be of the kind disclosed in the Felderman and Knoizen application, Serial No. 746,832, which comprises a portable body 3 mounted on wheels 4 and 5 adapted to travel over the floor of a mine. The body has a compartment adapted to carry a load of mine timbers and props, and extending lengthwise of the compartment beneath the bottom thereof and pivotally mounted on the body to swing horizontally with respect thereto is a horizontal arm 6. This arm projects outwardly from one end of the body and carries, at its free outer end, a vertical hydraulic jack 7 comprising telescopically arranged cylinder and piston elements, as fully disclosed in the above

3

mentioned copending application. Also carried by the arm 6 and projecting below the arm is a vertical hydraulic jack 8 for, at times, supporting the arm 6 and steadyng the upper jack 7.

The improved timber support 1 is preferably of a fabricated welded construction and is carried by the upper piston element 10 of the vertical jack 7 and comprises a horizontal bottom member or plate 11 having secured thereto, as by welding, a central hub 12 which is threaded, or otherwise, secured at 13 to the upper portion of the jack piston element 10, as shown in Figs. 3 and 6. The piston element 10 has a shoulder 14 which supports the bottom plate, as shown. Mounted on the top of the plate 11 is a centrally located support member 15 which may be secured, as by welding, to the bottom plate. The support member 15 is preferably square in shape and has a central opening 16 which receives the plate hub 12 so that the latter projects above the top of the support member. The support member 15 has a curved upper surface 17 struck on a radius from a point located below the support at the axial center of the jack piston element 10. An upper supporting member or plate 18 rests on the curved upper surface 17 of the central support at opposite sides of the latter so that the upper plate may rock or tilt about a transverse axis relative to the bottom plate, and the upper plate preferably has a central opening 19 of larger diameter than the diameter of the central hub 12 and into which the upper portion of the central hub projects with sufficient clearance to permit free limited tilting of the upper plate. By arranging the central hub of the bottom plate in openings in the support member 15 and upper plate 18, an extremely vertically compact structure is provided. The upper supporting plate has an upper plane surface 20 which provides a horizontal platform for receiving a mine timber which constitutes the load, and the upper plate has vertical side plates or flanges 21 for guiding a timber onto the platform and for preventing undesired lateral displacement of the timber from the platform. For retaining the upper plate 18 in position on the lower plate while permitting limited tilting of the upper plate, there are provided side retaining members 22 secured, as by screws 23, to the upper plate, as shown in Fig. 3. These retaining members have inner ledges or projections 24 which underlie the side edges of the central support member 15 and are formed with curved upper surfaces 25 (see Fig. 7) which contact the bottom of the support member. These curved surfaces 25 are struck on a smaller radius than the upper curved surface 17 of the central support member 15, with the axes of both surfaces in a plane in which the jack axis lies. The radius of the curved surfaces 25 of the side retaining members 22 is shorter than the radius of the curved surface 17 of the central support member 15 desirably by an amount exceeding the maximum thickness of the central support member. Thus the upper plate 18 may tilt about a transverse axis relative to the bottom plate while firmly retained in position on the bottom plate. Arranged transversely at the ends of the upper plate 18 are tubular reinforcing elements 26 secured, as by welding, to the ends of the upper plate, and these tubular elements provide curved end guide surfaces to facilitate movement of a timber onto the platform. As shown, the side flanges 21 extend along the length of the upper plate and across the ends of the tubular guides to provide

an extremely rigid platform structure. Secured, as by welding, to the side retaining plates or flanges 21 of the platform are inverted cup-shaped elements or spring housings 27 containing coil springs 28 which are guided and held under predetermined compression by bolts 29. These bolts have upper heads 30 engaging centering washers 31 for the upper ends of the springs, and the bolts extend downward freely through openings 32 in the bottom plate. Nuts 33, threaded on the lower ends of the bolts, engage the bottom of the bottom plate 11, and these nuts are locked in adjusted positions, i. e., when the springs are placed under the desired compression, by lock nuts 34 threaded on the bolts. The preloaded springs, which may be called equalizing springs, are so arranged and held in position by the bolts that the springs at one end of the platform do not expand when the platform is tilted down to compress the springs at its opposite end, and the preloaded springs serve to maintain the platform in a substantially horizontal position even when a timber thereon is slightly off-balance.

25 In use, the timber support may be turned with the upper piston element 10 of the jack into a position wherein the platform extends lengthwise of the body of the machine; and with the jack lowered, a timber, designated T in Fig. 1, 30 may be slid endwise from the body compartment of the machine onto the platform. The support and the timber thereon may then be turned manually into a position crosswise of the body, as shown in Fig. 1, and upon suitable supply of liquid under pressure to the pack, the support may be elevated to bring the timber up against the roof. When the timber is placed on the platform and is elevated by the jack, the preloaded springs prevent undesired tilting of the platform even 35 when the timber is somewhat off-balance on the platform. When the timber is elevated with the support and is held with considerable force up against the mine roof, and the roof is uneven, the platform may tilt on its spring mounting to enable the timber to accommodate itself to the 40 uneven roof. Thus, the timber may be firmly held up against the roof with the forces applied to the timber at points as near to the center of the jack as possible, and thereby protect the jack 45 from substantial lateral stresses.

As a result of this invention, an improved yieldably mounted, tilttable support is provided which is yieldingly maintained in substantially horizontal position even when the load thereon is somewhat off-balance, and is tilttable with the load only when the latter encounters substantial extraneous resistance, tending to tilt the load. It will further be evident that an improved spring-mounted, tilttable timber support is provided for a timber setting machine wherein the timber-receiving platform is maintained in substantially horizontal position by preloaded springs even when a timber is supported in substantially off-balance position thereon, and which is transversely tilttable when the timber is engaged with an uneven mine roof and substantial upward holding pressures are imparted to the support. The novel arrangement of the support parts provides for an extremely vertically compact structure. By the provision of the improved support structure embodying the tilttable plate and the mounting therefor, an extremely simple and rugged construction is attained. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a yieldably mounted, tilttable support, the combination comprising a base member, an elongated load receiving platform mounted on said base member to tilt about a transverse axis relative thereto, said axis of tilt located substantially midway between the ends of said platform, and preloaded yieldable elements arranged between said base member and said platform at points spaced equidistantly from the platform-pivot and on which said platform at the opposite sides of its pivot rests and is entirely supported at its ends when in horizontal position for normally preventing undesired tilting of said platform in the event a load is in slightly off-balance position thereon, means for maintaining said elements under a predetermined compression, said elements yieldable to permit tilting of said platform about said transverse axis only when the load has a substantial extraneous force imparted thereto tending to tilt the load, said yieldable elements at one end of said platform being further compressed as said end tilts downwardly relative to said base member due to unbalanced loading of said platform while the opposite end of said platform tilts upwardly away from said expanded preloaded yieldable elements at said opposite end whereby said upwardly tilted end is at that time supported on said base member wholly independently of said elements last referred to.

2. A spring-mounted tilttable support comprising, in combination, an elongated horizontal base member, an elongated horizontal load receiving platform arranged above said base member, means for pivotally mounting said platform on said base member substantially centrally between the ends thereof whereby when one end of said platform tilts downwardly the opposite end thereof tilts up, and preloaded springs arranged between said platform and said base member at points spaced from the platform-pivot for normally maintaining said platform in substantially horizontal position even when a load is in slightly off-balance position thereon, means for maintaining said springs under a predetermined compression, and said springs being further compressible at one said end of said pivot to permit tilting of one end of said platform downwardly at said side against the action of said springs only in the event a substantial extraneous force is imparted to the load tending to tilt the load, the opposite end of said platform as the latter tilts raising up relative to said fully expanded, preloaded springs at the opposite side of said pivot whereby said raised end of said platform is supported by said base member wholly independently of said springs last referred to.

3. A tilttable spring-mounted support comprising, in combination, an elongated horizontal base plate, an elongated horizontal upper plate arranged above said base plate and providing a load receiving platform, a centrally located support member carried by said base plate and having a curved upper surface on which the central portion of said upper plate rests and along which said upper plate is adapted to rock rela-

tive to said base plate, and pre-loaded springs arranged between said plates at the opposite sides of said support member for normally maintaining said upper plate in substantially horizontal position even when a load thereon is slightly off balance, means for maintaining said springs under a predetermined compression, said springs yieldable by further compression thereof to permit tilting of one end of said upper plate downwardly relative to said base plate against the action of said springs at one side of the pivot only when a substantial extraneous force is imparted to the load tending to tilt the load, the opposite end of said platform as the latter is tilted moving away from the fully expanded preloaded springs at the opposite side of the pivot whereby said raised end of said platform is supported by said base plate wholly independently of said springs last referred to.

20 4. A tilttable spring-mounted support, comprising, in combination, an elongated horizontal base plate, a horizontal upper plate arranged above said base plate and providing a load receiving platform, a centrally located support member carried by said base plate and having a curved upper surface on which said upper plate rests and along which said upper plate is adapted to rock relative to said base plate, means for retaining said upper plate in position on said central support member including a retaining element secured to said upper plate and having a curved surface struck on a smaller radius than the curved upper surface of said support member and contacting the lower surface of said support member, and preloaded springs arranged between said plates at the opposite sides of said support member for maintaining said upper plate in substantially horizontal position even when a load thereon is slightly off balance, and yieldable to permit tilting of said upper plate relative to said base plate against the action of certain of said springs only when a substantial extraneous force is imparted to the load tending to tilt the load.

45 5. In a spring-mounted, transversely tilttable support, the combination comprising a horizontal base plate, an elongated horizontal upper plate arranged above said base plate and providing a load receiving platform, a relatively fixed centrally located pivot member carried by said base plate and on which said upper plate rests between its ends and on which said upper plate is adapted to rock relative to said base plate, and spring connections between said plates at points spaced 50 from said pivot member including inverted cup-shaped spring housings secured to said upper plate, springs arranged in said housings and engaging the upper surface of said base plate, and bolts arranged centrally of said springs between the latter and said base plate for maintaining said springs under a predetermined compression whereby said springs normally tend to hold said upper plate against tilting even when a load is in slightly off-balance position thereon, and said 55 springs further compressible at one side of the pivot to permit tilting of one end of said upper plate downwardly only when a substantial extraneous force is imparted to the load tending to tilt the latter, said upper plate as its opposite end tilts upwardly moving away from said fully expanded, preloaded springs at the opposite side of the pivot, and said latter springs at that time held against expansion by their associated bolts, said upper plate when in said tilted position being supported by said base plate wholly inde- 60 70 75

pendently of said preloaded springs last referred to.

6. A spring-mounted, tilttable support adapted for use with the elevating jack of a timber setting machine, comprising, in combination, a horizontal base member carried by an adjustable element of said jack, an elongated timber receiving platform pivotally mounted on said base member to tilt on a relatively fixed pivot about a transverse axis relative to said base member, said axis of tilt located substantially midway between the ends of said platform, and preloaded spring connections arranged between said platform and said base member at points spaced from the opposite sides of said pivot axis for normally maintaining said platform in substantially horizontal position even when a timber is received thereon in slightly off-balance position, means for maintaining said springs under a predetermined compression, said springs yieldable by further compression thereof to permit tilting of said platform only when the timber is held up with substantial force by said jack against an uneven mine roof, said platform as it tilts downwardly at one end further compressing the springs at 15 that side of the pivot while the opposite end of said platform tilts upwardly away from the fully expanded, preloaded springs at the opposite side of the pivot whereby said raised end of said platform is at that time wholly supported by said 20 base member independently of said preloaded springs last referred to.

7. A yieldably mounted, tilttable support comprising, in combination, a base member having a central upstanding hub, a centrally located support member having an opening through which which said hub extends, a horizontal platform arranged above said base member and pivotally mounted on said support member, said platform having a central opening for receiving the upper portion of said hub and of larger size than said hub to provide clearance to permit tilting of said platform relative to said base member, and yieldable spring connections between said platform and said base member at opposite sides of said central support in spaced relation with respect to the pivot.

8. A yieldably mounted, tilttable support comprising, in combination, a base member having a central upstanding hub, an elongated horizontal platform arranged above said base member, means for pivotally mounting said platform on said base member to tilt about a transverse axis located substantially midway between the ends of said platform, said pivotal mounting means maintaining said platform against tilting about a longitudinal axis, said platform having a central opening into which said hub projects and of larger size than said hub to provide clearance to permit tilting of said platform relative to said base member, and yieldable connections between said base member and said platform at the opposite sides of said pivotal mounting means in equidistant spaced relation with respect to the transverse pivot for normally maintaining said platform in a horizontal position even when supporting an unbalanced load.

9. A yieldably mounted, tilttable support comprising, in combination, a base member having a central upstanding hub, a central support member having an opening through which said hub extends, said central support having a curved upper surface, a horizontal platform resting between its ends on said curved surface of said central support and having a central opening into

5 which the upper portion of said hub extends and of a larger size than said hub to provide clearance to permit tilting of said platform relative to said base member, and yieldable spring connections between said platform and said base member at opposite sides of said central support in spaced relation with respect to the pivot.

10. A yieldably mounted, tilttable support comprising, in combination, a base member having a central upstanding hub, a central support member having an opening through which said hub extends, said central support having a curved upper surface, a platform resting on said curved surface of said central support and having a central opening into which the upper portion of said hub extends and of a larger size than said hub to permit tilting of said platform, retaining members secured to said platform and underlying said central support and having curved surfaces struck on a smaller radius than said curved surface of said central support to permit tilting of said platform relative to said central support, and yieldable spring connections between said platform and said base member at opposite sides of said central support.

11. A yieldably mounted, tilttable support comprising, in combination, a base member, an elongated horizontal load-receiving platform overlying said base member, means for pivotally mounting the central portion of said platform on said base member to rock relative to said base member about a horizontal axis, coil springs carried by said base member near its ends and spaced equidistantly from said transverse axis, and means connected to said base member and engaging the upper ends of said springs for compressing the latter to maintain said springs under a predetermined load, said platform when in its normal horizontal position resting on said preloaded springs at opposite sides of its pivotal mounting, and said platform as one end tilts downwardly due to unbalanced loading thereof further compressing the springs at the adjacent side of said pivotal mounting while the opposite end of said platform tilts upwardly relative to said base member away from the expanded preloaded springs at the other side of said pivotal mounting whereby said upwardly tilted end of said platform is at that time supported on said base member wholly independently of said springs last referred to.

12. A yieldably mounted, tilttable support comprising, in combination, a base member, an elongated horizontal load-receiving platform overlying said base member, means for pivotally mounting said platform between its ends on said base member to rock relative thereto about a horizontal transverse axis, said mounting means including a member carried by said base member and having a curved upper surface against which the bottom of said platform rests, coil springs carried by said base member at the opposite sides of said pivotal mounting and spaced equidistantly from said transverse axis, and means connected to said base member and engaging the upper ends of said springs for compressing the latter to maintain said springs under a predetermined load, said platform when in its normal horizontal position resting against said springs whereby said preloaded springs hold said platform in such horizontal position, and said platform as it tilts downwardly at one end due to unbalanced loading thereof further compressing the springs at the adjacent side of said pivotal

mounting while the opposite end of said platform tilts upwardly relative to said base member away from the expanded preloaded springs at said other side of said pivotal mounting whereby said upwardly tilted end of said platform is at that time supported on said base member wholly independently of said springs last referred to.
